Attorney

United States Patent Office.

JOSEPH DUNOTT, OF PHILADELPHIA, PENNSYLVANIA, ASSIGNOR TO HIMSELF AND GEORGE GIBSON, OF SAME PLACE.

Letters Patent No. 97,620, dated December 7, 1869.

IMPROVED CAR-COUPING.

The Schedule referred to in these Letters Patent and making part of the same.

To all whom it may concern:

Be it known that I, JOSEPH DUNOTT, of Philadelphia, in the county of Philadelphia, and State of Pennsylvania, have invented a new and useful Improvement in Car-Coupling; and I do hereby declare that the following is a full and exact description of the same, reference being had to the accompanying drawings, and to the letters of reference marked thereon.

This invention relates to that class of car-couplings which is automatic in their action; and consists mainly in the combination of a revolving keeper in the lower part of the draw-head, with a swinging keeper in the upper part, by means of which the link is securely held.

It further consists, also, in certain details of construction, which, in connection with the foregoing, will be fully described hereinafter.

In the drawings—

Figure 1 represents a longitudinal sectional elevation, showing the swinging keeper in its natural position;

Figure 2 represents the same view, with the keeper elevated;

Figure 3 represents a transverse sectional elevation; and

Figure 4, a perspective view of the swinging keeper.

To enable others skilled in the art to make and use my invention, I will now proceed to describe its construction and operation.

A represents the draw-head of a car, which is provided with the longitudinal slot *a*, and transverse orifice *a'*.

B represents a shaft, which fits into the orifice *a'*, and turns freely therein. Upon this shaft is located the keeper C, as shown in figs. 1 and 2.

D represents a swinging keeper, which is pivoted in the upper part of the draw-head, the motion of which, however, is limited to the perpendicular line *x*, as shown.

E represents a slide, which, when in position, is located behind the keeper D, for the purpose of preventing it from being accidentally thrown upward.

F represents a pocket, in which the slide E is placed when not needed for use.

G represents the link, which is preferably constructed of steel, and made thin in the centre, in order to permit the necessary play incidental to the vibration of the cars. If desired, it may be constructed of a steel

band, and strengthened with iron plates about the orifices.

To the shaft B is attached a lever, which rises above the platform to any point convenient for operating it. It is ordinarily secured in place by a spring-catch or other similar device.

The foregoing description relates to the draw-head which is used for uncoupling. The other draw-head of the pair is constructed in all points like this, excepting that the shaft B is omitted, and a projection similar to the part of the keeper C, exposed above the lower surface of the draw-head A, is cast upon the corresponding part of the draw-head H.

The operation is as follows:

The link ordinarily remains securely held in draw-head H. As the cars come together, its free end enters draw-head A, strikes upon the inclined side of the keeper C, swings back the keeper D, and, falling behind the keeper C, is securely fastened in this position by the keeper D, which swings back into place by its own weight. If it is desired to lock it in this position, the slide F is placed in the proper orifice, when it becomes impossible for the cars to become accidentally uncoupled.

When it is desired to uncouple the cars, however, the lever attached to the shaft is disconnected from the spring-catch by which it is held, and thrown forward. By this operation, the keeper C is moved below the line of the draw-head, and the link is free to come out.

By the construction herein described, an extremely simple and efficient coupling is produced.

Having thus fully described my invention,

What I claim as new, and desire to secure by Letters Patent, is—

1. The combination of the revolving keeper C with the swinging keeper D and shaft B, substantially as described, for the purpose set forth.

2. The draw-head A, with shaft B, keepers C D, and slide E, when arranged and operated as described, for the purpose set forth.

This specification signed and witnessed, this 23d day of October, 1869.

JOSEPH DUNOTT.
